UNITED STATES PATENT OFFICE.

MARY KNAPP, OF DAYTON, NEW YORK.

THREAD AND SEWING-SILK REGULATOR FOR SEWING-MACHINES.

No. 899,451.

Specification of Letters Patent.

Patented Sept. 22, 1908.

Application filed April 17, 1908. Serial No. 427,725.

To all whom it may concern:

Be it known that I, MARY KNAPP, a citizen of the United States of America, residing at Dayton, in the county of Cattaraugus and 5 State of New York, have invented new and useful Improvements in Thread and Sewing-Silk Regulators for Sewing-Machines, of which the following is a specification.

This invention relates to thread and sewing 10 silk regulators for sewing machines, and one of the principal objects of the same is to provide a simple and efficient device to be placed upon the spool post of the sewing machine to prevent the thread from winding around the 15 post.

In using silk thread or wax thread on sewing machines, when the spool is placed upon the spool post, it is very liable to slip off the spool and to wind around the post as soon as 20 the feed begins to draw upon the thread. My invention is intended to overcome this annoyance.

In the accompanying drawing,—Figure 1 is a perspective view illustrating my thread 25 and sewing silk regulator applied to the spool post of a sewing machine, only a portion of the latter being shown. Fig. 2 is a side view of my attachment. Fig. 3 is an edge view of the same. Fig. 4 is an underside plan view.

30 Referring to the drawing for a more specific description of my invention, the numeral 1 designates the spool post, usually located on the arm 2 of a sewing machine.

My invention consists of an upright arm 3 35 provided with a plurality of thread guiding eyes 4 in the flattened upper portion of the same and inclined slots 5 leading from the outer edge of said arm into the eyes 4. The eyes 4 are very smooth so that the thread 40 will run freely through the same. A hori-

zontal member 6 is provided with a suitable supporting device for the attachment. As shown, a disk 7 is provided with a sleeve 8 having a hole 9 therein of a size to slip readily over the spool post 1. A set screw 10 passes 45 through the sleeve 8 to bear against the spool post 1 and hold the attachment firmly in place. There being two eyes 4 in the arm 3, spools of different height may be used and the thread prevented from running off the 50 spools and winding on the post by using the upper eye for a long spool and the lower eye for a short one. Silk thread and wax thread are very liable to slip off the spool immediately after the spool is placed upon the post, 55 and my attachment is particularly designed for use with wax thread or silk.

My thread and sewing silk regulator may be manufactured at slight cost, can be quickly applied for use and has been found 60 very desirable and efficient for its purpose.

Having thus described the invention, what is claimed as new, is:—

A thread and sewing silk regulator for sewing machines comprising a disk, an arm extending outwardly therefrom, a vertical arm connected thereto and provided with a flattened upper end, thread eyes formed in the flattened portion and provided with inclined slots leading into said eyes, a sleeve under 65 said disk, and a set screw extending through said sleeve to bear upon the spool post of a 70 sewing machine.

In testimony whereof I affix my signature in presence of two witnesses.

MARY KNAPP.
